UNITED STATES PATENT OFFICE.

JOHN M. BARR, OF PITTSBURGH, PENNSYLVANIA, ASSIGNOR TO WESTINGHOUSE ELECTRIC & MANUFACTURING COMPANY, A CORPORATION OF PENNSYLVANIA.

ELECTRICAL APPARATUS.

1,013,108.

Specification of Letters Patent.

Patented Jan. 2, 1912.

Application filed July 17, 1905. Serial No. 270,090.

To all whom it may concern:

Be it known that I, JOHN M. BARR, a citizen of the United States, and a resident of Pittsburgh, in the county of Allegheny and State of Pennsylvania, have invented a new and useful Improvement in Electrical Apparatus, of which the following is a specification.

My invention relates to electrical apparatus and it has special reference to apparatus having means for varying the magnetizing effect of its winding or windings.

The object of my invention is to provide an apparatus of the general character above indicated that shall have a flexible winding which may be either disposed upon its core in two or more equal and opposing coils or be adjusted to provide either opposing or assisting turns of any number between the limits imposed by the length of the winding.

My invention is primarily intended for alternating current voltage regulation, and I will therefore describe it as applied to such use. I believe the invention to be of broader scope and suitable for other uses, however, and I therefore desire it to be understood that no specific application which may be hereinafter described shall be held to exclude any alternating current or direct current apparatus the structural and operative characteristics of which are the equivalents of those here set forth, even though such apparatus may be utilized in different relations to effect a specifically different result.

Potential regulators, as heretofore constructed, may be divided into two general classes, one of which embodies transformers that are provided with a plurality of taps entering their windings at various points to which one side of a circuit is successively connected to vary the voltage applied thereto and therefore involves numerous circuit interruptions. The other class of regulators depends for its operation upon the position of a winding on a rotatable core or armature with respect to a stationary winding which is in inductive relation thereto. This construction involves a considerable air-gap in the magnetic circuit and a careful alinement of the rotating member, which makes the construction relatively expensive.

The regulator of my invention may be constructed with a comparatively inexpensive core and may effect a wide regulation without circuit interruptions. In general,

it comprises a winding composed of flexible conductors in the form of cable, wire-braid or a chain of metal links, so that it may be readily wound and removed without injuring the conductor itself or its insulation and may be movably mounted upon a magnetizable core. One end of the flexible winding may be connected to a movable contact member, such as a slip-ring, through which it may be continuously connected to an electric supply circuit. A considerable number of turns may be then wound upon one portion of a magnetizable core, which may be magnetized by a fixed winding, and the other end of the flexible winding may be connected to another slip-ring on another portion of the magnetizable core. The portions of the core that are engaged by the flexible winding may be either rotatable with respect to the remainder of the core or may be provided with spools or bobbins which are rotatably mounted thereon, though I do not claim to be the originator of the specific construction that embodies the rotatable core portions. Means may be provided for simultaneously rotating the two portions of the core or the two bobbins, as the case may be, in such manner that the turns of the flexible winding shall be transferred from one portion of the core to the other and the electromotive forces generated in the turns on one portion shall oppose the electromotive forces generated in the turns on the other portion of the core. In this way, all the turns of the flexible winding may act magnetically in the one direction or the other, or the magnetizing effect of the winding may be either partially or wholly neutralized by the opposing action of its two parts. If such a flexible winding is connected in series with a circuit and the stationary magnetizing winding is connected across the same circuit, the flexible winding may be varied to regulate the electromotive force applied from the circuit without any circuit interruptions.

If it is desirable to substantially change the value of voltage about which the regulation takes place, two fixed magnetizing windings may be employed, as in an ordinary transformer, in which case the flexible winding of my invention may be connected in series with the fixed secondary winding and the circuit to which energy is supplied, while the primary magnetizing winding

may be connected to the circuit from which energy is received.

When collector rings are mounted in such a position that the magnetic flux in the core passes through them, it is advisable to provide an opening in the ring in which insulation may be inserted to prevent the induction of a short-circuited current in the ring and, in regulation, where such short-circuited currents would be excessive, a pair of narrow brushes, which are connected by an inductive or other suitable resistance, may be advantageously employed to engage the ring at different points, the circuit connection being made to the middle point of the interposed resistance instead of to a single brush, which would in some instances short-circuit the ring or break the circuit.

My invention is illustrated in the accompanying drawings, in which—

Figure 1 is a diagrammatic view of a regulator constructed in accordance therewith, in which two opposite portions of the core are rotatably mounted. Fig. 2 is a similar view, in which spools or bobbins are rotatably mounted on two opposite fixed portions of the core. Fig. 3 is a diagrammatic view of the circuit connections of the regulators disclosed in Figs. 1 and 2, and Fig. 4 is a view, similar to Fig. 2, of a regulator that is provided with independent fixed primary and secondary windings in addition to the regulating winding of my invention.

Referring to Figs. 1 and 3, a magnetizable core 1 comprises two fixed portions 2 and 3 and a plurality of rotatably mounted portions 4 and 5 that are provided with shaft extensions 6 and 7 upon which slip-rings 8 and 9 and pinions 10 and 11 are mounted. The rotatable portions may be simultaneously driven, through the pinions 10 and 11, by a gear-wheel 12 which engages the pinions and may be driven by any convenient means, such, for example, as a hand-wheel 13. The slip-rings 8 and 9 are insulated from their respective shafts and are connected to opposite ends of a flexible winding 14, which is coiled about the rotatable core portions 4 and 5 in such a way that its turns may be distributed between the two portions or may be entirely wound on either portion, their position and distribution being determined by the simultaneous rotation of the cores upon which they are mounted. The core 1 may be further provided with a fixed magnetizing coil 15, which is connected across an electric supply circuit 16—17 and is supplied with energy therefrom. The slip-rings 8 and 9 are engaged by a pair of brushes 18 and 19, which are connected in series with the line conductor 17, so that the entire circuit current passes through the flexible winding 14 except that which is supplied to the stationary coil 15.

When all the turns of the winding 14 are

on the rotatable core portion 4, the electro-motive force induced therein is in the same direction as that of the line 16—17, so that its value is added to that of the line. When the turns in the winding 14 are evenly distributed between the two core portions 4 and 5, the electromotive forces induced in the two portions oppose each other, substantially neutralizing their effect upon the line, and when the turns of the winding 14 are all transferred to the portion 5, the electromotive force induced therein is opposed to that of the line, so that the voltage therefrom is less than the line voltage. Any variation between these two values may be obtained by proper distribution of the turns of the winding 14 between the core portions 4 and 5.

Referring to Fig. 2, a magnetizable core 20 corresponds to that of Fig. 1 and comprises a continuous magnetic circuit the portions of which are relatively fixed. A plurality of spools or bobbins 21 and 22 are rotatably mounted upon the two opposite portions of the core 20. The flexible winding 23, which corresponds to the winding 14 of Figs. 1 and 3, is wound upon the spools 21 and 22 and its ends are respectively connected to slip-rings 24 and 25. Each of the rings 24 and 25 is preferably provided with a short insulating segment 25^a in order to prevent the generation of secondary currents therein. Two brushes 26 are provided to make contact with the ring 24 and may be connected to the ends of a preventive resistance 26^a. The ring 25 is similarly provided with two brushes 27 that may be connected to the terminals of a preventive resistance 27^a. The middle points of the preventive resistances 26^a and 27^a are connected to the interrupted line conductor 28 in such manner as to include the winding 23 in series in the main circuit.

Any suitable means for driving the spools 21 and 22 may be employed, such as gear wheels 30 and 31, which are keyed to the spools, and a similar gear-wheel 32 that may be actuated by a hand-wheel 33 or otherwise. The magnetizing winding 36 may be located and connected in circuit substantially as in the modification shown in Fig. 1.

Referring to Fig. 4, energy is supplied from an electric supply line 34—35 to a primary magnetizing winding 36, which corresponds to the fixed winding 15 of Figs. 1, 2 and 3 and is mounted upon a magnetizable core 27. An independent fixed secondary winding 38 is mounted upon the core 37 and is connected in series with a flexible winding 39, which corresponds to the windings 14 and 23 of Figs. 1 and 2.

In the system shown in Fig. 4, the energy for the work circuit 40—41 is supplied by the winding 38 which, in turn, receives its energy, by induction, from the winding 36, the

system being different from that shown in Fig. 2 only in having two inductively related circuits in place of a single circuit.

I claim as my invention:

5. 1. The combination with a magnetizable core and a flexible winding therefor, of means for transferring a part or all of the turns of the winding from one portion of said core to another in such a manner as to wholly or partially neutralize its effect or to make it maximum in either direction.
10. 2. The combination with a magnetizable core and a flexible winding therefor, of means for transferring a part or all of the turns of the winding from one portion to another portion of said core.
15. 3. The combination with a magnetizable core and a flexible winding therefor that it is permanently connected in an electric supply circuit, of means for transferring a part or all of the turns of the winding from one portion to another portion of said core.
20. 4. The combination with a magnetizable core, a magnetizing winding and a flexible regulating winding therefor, of means for transferring the turns of said regulating winding from one portion to another portion of said core without disconnecting the regulating winding.
25. 5. The combination with an electric circuit and a voltage regulator therefor comprising a magnetizable core and a plurality of magnetizing windings therefor, one of which is flexible and is connected in series 30 relation to said circuit, of means for transferring a part or all the turns of the flexible winding from one portion to another portion of the core without interrupting the connections of the windings.
35. 6. The combination with a magnetizable core and a plurality of windings therefor, of means for so transferring all or a part of the turns of one portion of the winding from one part of the core to another, that 40 said turns may either aid or oppose the turns of the remaining portion of the winding.
45. 7. The combination with an electric supply line, of means for regulating the voltage applied therefrom that comprises a stationary winding and a flexible series winding which are wound on the same magnetic core, and means for transferring all or a part of the turns of said series winding from one 50 portion to another portion of said core.
55. 8. The combination with a magnetizable core, a fixed magnetizing winding therefor and a pair of rotatable spools surrounding portions of the core, of a flexible magnetizing winding located on said spools, and means for transferring the turns of the flexible coil from one spool to the other.
60. 9. The combination with an electric circuit and means for regulating the voltage thereof that comprises a magnetizable core, 65 a stationary magnetizing winding, a flexible series winding and means for transferring the turns of the flexible winding from one portion of the core to another portion without interrupting the circuit connections of 70 said winding.
65. 10. The combination with an electric supply circuit, of a voltage regulator comprising a magnetizable core, a primary magnetizing winding connected to said supply circuit, a secondary winding, and means for transferring any desired number of turns of said secondary winding from one portion of the core to another portion thereof.
70. 11. The combination with a magnetizable core provided with a rotatable member, a fixed magnetizing winding for said core and a flexible winding wound on the rotatable member, of means for removing and replacing one or more turns of said flexible winding without disconnecting it from its circuit.
75. 12. The combination with a magnetizable core, a magnetizing winding therefor, a plurality of spools or bobbins rotatably mounted thereon, a collector ring and a gear pinion mounted on each spool, and means for simultaneously rotating said spools, said means comprising a driving shaft which is provided with a gear wheel to engage said pinions, of a flexible winding disposed on 80 said spools and connected to said collector rings.
80. 13. The combination with a magnetizable core, a magnetizing winding therefor, a plurality of spools or bobbins rotatably mounted thereon, a collector ring and a gear pinion mounted on each spool, and means for simultaneously rotating said spools, said means comprising a driving shaft which is provided with a gear wheel to engage said 85 pinions, of a flexible winding disposed on said spools and connected to said collector rings.
85. 14. The combination with a magnetizable core, a pair of spools or bobbins rotatably mounted thereon, and a primary magnetizing winding therefor, of a flexible secondary winding one or more turns of which are wound on said spools and are transferred from one portion of the core to another portion by the simultaneous rotation of the 90 spools.
90. 15. The combination with a source of alternating current electrical energy, a magnetizable core, a pair of spools or bobbins rotatably mounted thereon, and a primary magnetizing winding therefor that is connected to said source, of a flexible secondary winding connected to said source, one or more turns of which are wound upon said spools and are transferred from one portion 95 of the core to another portion.
95. 16. The combination with a magnetizable core, a pair of spools or bobbins rotatably mounted thereon, and a primary magnetizing winding therefor, of a flexible secondary winding one or more turns of which are wound upon said spools and are transferred from one portion 100 of the core to another portion.
100. 17. The combination with a magnetizable core, a pair of spools or bobbins rotatably mounted thereon, and a primary magnetizing winding therefor, of a flexible secondary winding one or more turns of which are wound upon said spools and are transferred from one portion 105 of the core to another portion.
105. 18. The combination with a magnetizable core, a pair of spools or bobbins rotatably mounted thereon, and a primary magnetizing winding therefor, of a flexible secondary winding one or more turns of which are wound upon said spools and are transferred from one portion 110 of the core to another portion.
110. 19. The combination with a magnetizable core, a pair of spools or bobbins rotatably mounted thereon, and a primary magnetizing winding therefor, of a flexible secondary winding one or more turns of which are wound upon said spools and are transferred from one portion 115 of the core to another portion.
115. 20. The combination with a magnetizable core, a pair of spools or bobbins rotatably mounted thereon, and a primary magnetizing winding therefor, of a flexible secondary winding one or more turns of which are wound upon said spools and are transferred from one portion 120 of the core to another portion.
120. 21. The combination with a source of alternating current electrical energy, a magnetizable core, a pair of spools or bobbins rotatably mounted thereon, and a primary magnetizing winding therefor that is connected to said source, of a flexible secondary winding connected to said source, one or more turns of which are wound upon said spools and are transferred from one portion 125 of the core to another portion.
125. 22. The combination with a magnetizable core, a pair of spools or bobbins rotatably mounted thereon, and a primary magnetizing winding therefor, of a flexible secondary winding one or more turns of which are wound upon said spools and are transferred from one portion 130 of the core to another portion.

of the core to another portion by simultaneous rotation of the spools.

16. The combination with a magnetizable core, a pair of spools or bobbins rotatably mounted thereon, a primary magnetizing winding therefor, means for simultaneously rotating said spools, and a source of alternating current electrical energy connected to said primary winding, of a secondary winding having a plurality of turns mounted upon said rotatable spools and so transferable from one spool to the other, as said spools are rotated, that the electromotive force induced therein acts in either direction or wholly or partially neutralizes itself.

17. The combination with a source of alternating current energy, a magnetizable core, a primary magnetizing winding mounted upon said core and energized from said source, and a secondary winding for supplying energy to an external circuit, of means for transferring one or more turns of the secondary winding from one portion of the core to another portion thereof.

25. 18. The combination with a source of alternating current energy, a magnetizable core, a primary magnetizing winding mounted upon said core and energized from said source, and a secondary winding for supplying energy to an external circuit, of means for transferring one or more turns of the secondary winding from one portion of the core to another portion thereof, said means comprising a plurality of spools or bobbins rotatably mounted upon said magnetizable core and means for simultaneously rotating the spools.

19. A voltage regulator for electrical distributing systems including a transformer and means for winding and unwinding one of its conductors to vary the effective voltage of one of its circuits.

20. In a voltage regulator for electrical distributing systems, a transformer and a reel for supporting part of its winding, whereby the voltage may be varied by shifting the winding upon and from the reel.

21. In a voltage regulator for systems of electrical distribution, a transformer and two rotary elements upon which part of its winding is adapted to be wound and unwound.

22. In a voltage regulator for systems of electrical distribution, a transformer having a part thereof around which a secondary winding is placed, and around which the secondary winding is adapted to be wound and unwound.

23. In a voltage regulator, the combination with a primary and secondary winding, and means energized by the primary current for generating the voltage in the sec-

ondary winding, and a reel upon which the secondary winding is adapted to be wound and unwound for varying said voltage.

24. In a voltage regulator, a transformer, a reel and a conductor thereon, surrounding the core of the transformer and upon which said conductor is adapted to be wound and unwound.

25. In a voltage regulator for electrical distributing systems, a transformer and reels carrying part of its winding in its magnetic field, said winding being adapted to be wound and unwound from one reel to another.

26. A voltage regulator for electrical distributing systems including a transformer and means for winding and unwinding one of its conductors to vary the effective voltage of one of its circuits, and means for taking the current to and from said circuit.

27. In a voltage regulator for electrical distributing systems, a transformer, and a reel for supporting part of its winding, whereby the voltage may be varied by shifting the winding upon and from the reel, and means for taking the current to and from the winding.

28. In a voltage regulator for systems of electrical distribution, a transformer and two rotary elements upon which part of its winding is adapted to be wound and unwound, and means for taking the current to and from said winding.

29. In a voltage regulator for electrical distributing systems, a transformer, and a reel for supporting part of its winding, in combination with means for collecting the current from said winding and preventing short-circuiting of the transformer.

30. In a voltage regulator for electrical distributing systems, a transformer, and a reel for supporting part of its winding, in combination with a current-collecting segment and brushes for taking current to and from said segment.

31. In a voltage regulator for electrical distributing systems, a transformer, reels upon which the secondary winding of the transformer is adapted to be wound and unwound in such manner that the part wound upon one reel has generated in it a voltage in opposition to that generated in the part wound upon the other reel, in combination with means for taking the current to and from the secondary winding.

In testimony whereof, I have hereunto subscribed my name this 8th day of July, 1905.

JOHN M. BARR.
